UNITED STATES PATENT OFFICE

WILHELM B. BRONANDER, OF MONTCLAIR, NEW JERSEY

FIRE-EXTINGUISHER SUPPORT

Application filed March 7, 1928. Serial No. 259,763.

This invention relates to fire extinguisher supports.

More particularly stated, the invention relates to the grenade type of fire extinguisher and to a holder or support for the grenade.

This invention has for its salient object to provide a support for a grenade so constructed that the grenade can be easily and readily removed therefrom and, furthermore, so constructed and arranged that in case of fire the grenade will be automatically broken and will dispense the fire extinguishing fluid.

Another object of the invention is to provide a bracket or holder for grenades comprising few parts and a structure that can be economically manufactured.

Another object of the invention is to provide a fire extinguisher support or grenade holder so constructed and arranged that a plurality of grenades can be supported in a manner whereby they will be automatically released and broken in case of fire.

Further objects of the invention will appear from the following specification taken in connection with the drawings, which form a part of this application, and in which—

Fig. 1 is an elevational view illustrating one form of the support constructed in accordance with the invention;

Fig. 2 is a side elevation of the structure shown in Fig. 1;

Fig. 3 is an elevational view partly in section showing a ceiling support constructed in accordance with the invention;

Fig. 4 is an elevational view showing a plurality of supports constructed in accordance with the invention and adapted for successive operation;

Fig. 5 is a side elevation of a slight different form of support constructed in accordance with the invention; and

Fig. 6 illustrates another form of support adapted particularly for use with ceilings.

The invention briefly described consists of a grenade supporting structure comprising a bracket, a member or an arm pivotally associated with the bracket and having means for supporting and holding a grenade, resilient means for swinging the arm relative to the bracket, and heat controlled means for hold-

ing the arm against swinging movement. In certain forms of the invention a plurality of arms are mounted on the bracket and are adapted to swing relative to each other and to the bracket, and heat controlled means is provided for holding the arms against swinging.

Further details of the invention will appear from the following description.

In the form of the invention illustrated in Figs. 1 and 2 there is shown a bracket 10 having a stud 11 projecting laterally therefrom. Two arms 12 and 13 are mounted on the stud and are adapted to swing relative thereto.

In this particular embodiment of the invention the arms are formed integral with a pair of springs 15 and 16, each spring having one end 17 fixed to the stud 11. Each arm has a loop 20 at the upper end thereof adapted to rest on the upper end portion of a grenade 21 and each arm also has a loop 22 adapted to receive the lower end of the grenade.

Each of the loops 20 has formed therein an eye 26 adapted to be engaged by a fusible link 27 which holds the arms against separation.

In the embodiment of the invention shown in Figs. 1 and 2, the arms, loops and springs are all integral and the springs tend to swing the arm 12 in one direction, indicated by the arrow X, and tend to swing the other arm in the opposite direction, indicated by the arrow Y, the arms being held under tension by the fusible or heat controlled link 27.

An arm 30 extends downwardly from the stud 11 and is provided at its lower end with spikes 31 and 32 adapted to be engaged by the grenades when they are released and to break the grenades. If desired the arm 30 can be dispensed with and the grenades will be swung into contact with each other, thus causing them to break and release the fire extinguishing fluid contained therein.

It will be evident that the grenades can be easily and readily removed from the supports by lifting the upper loops 20 so that they can be thrown at the fire if any one is present when the fire breaks out.

In Fig. 3 a pair of supports of the type il-

lustrated in Figs. 1 and 2 is shown mounted on a ceiling 35.

Fig. 4 illustrates a plurality of grenade supporting structures 40, 41 and 42 mounted on a wall. These devices can be arranged by using different compositions of fusible links in such a manner that the grenades will be released successively. For instance, the link in the device 40 will be so chosen that it will 10 release the grenades at a predetermined temperature, such, for instance, as 125°. The links of the devices 41 and 42 may be of such composition that they will release the grenades in these devices at 130° and 135° respectively. In this way an accumulative effect 15 of the fire extinguishing fluid released by the successive releasable devices may be obtained.

In Fig. 5 there is shown a support comprising 20 a back plate or bracket plate 50 having an arm 51 pivotally associated therewith and preferably formed of resilient material, one end of the arm constituting a spring, the free end of the spring being secured as shown 25 at 52 to the plate 50.

The arm 51 is provided with a pair of loops 53 and 54 preferably formed integral with the arm and adapted to engage and support the grenade 21.

30 The upper loop 53 has an eye 55 which is engaged by a fusible link 56, the other end of the link being secured at 57 to the back plate.

The plate 50 has secured thereto adjacent the lower end a spike 60 adapted to be engaged by the grenade when the grenade is released by the fusible link.

In Fig. 6 there is shown another form 40 of the invention adapted for use on a ceiling. This device is similar to that illustrated in the preceding figures and comprises an arm 65 pivotally associated with a bracket 66 and having a grenade retaining and holding means 67 and 68 carried thereby. The arm is held under spring tension by a fusible 45 link 70 and is adapted when released to swing upwardly and strike the ceiling. The bracket may, if desired, be provided with a spike positioned to be engaged by the grenade when the grenade is released.

50 By the term "grenade" as used in the specification and claims is meant a frangible container having a fire extinguishing fluid therein.

Although certain specific embodiments of 55 the invention have been particularly shown and described, it will be understood that the invention is capable of modification and that changes in the construction and in the arrangement of the various cooperating parts 60 may be made without departing from the spirit or scope of the invention, as expressed in the following claims.

What I claim is:

1. Grenade supporting structure for frangible 65 grenades comprising a bracket, a resil-

ient supporting member carried by said bracket and mounted to swing thereon through a definite path of movement, means carried by said member for supporting and holding a grenade, and means disposed in the path of movement of the grenade for breaking the grenade upon impact therewith. 70

2. Grenade supporting structure for frangible 75 grenades comprising a bracket, a resilient supporting member carried by said bracket and mounted to swing thereon through a definite path of movement, means carried by and formed integral with said member for supporting and holding a grenade, and means disposed in the path of movement of the grenade for breaking the grenade upon impact therewith. 80

3. Grenade supporting structure for frangible 85 grenades comprising a bracket, a resilient supporting member carried by said bracket and mounted to swing thereon through a definite path of movement, means carried by said member for supporting and holding a grenade, means for holding said member under tension, and means disposed in the path of movement of the grenade for breaking the grenade upon impact therewith. 90

4. Grenade supporting structure for frangible 95 grenades comprising a bracket, a resilient supporting member carried by said bracket and adapted to swing thereon, means carried by said member for supporting and holding a grenade, fusible means for holding said member under tension, and means disposed in the path of movement of the grenade for breaking the grenade upon impact therewith. 100

5. Grenade supporting structure for frangible 105 grenades comprising a bracket, an arm pivotally associated therewith and having means for supporting and holding a grenade, resilient means for swinging said arm on the bracket through a path of movement about the pivot thereof, means for holding said arm from swinging, and means disposed in the path of movement of the grenade for breaking the grenade upon impact therewith. 110

6. Grenade supporting structure comprising 115 a bracket, an arm pivotally associated therewith and having means for supporting and holding a grenade, resilient means for swinging said arm on the bracket, heat controlled means for holding said arm from swinging, and means disposed in the path of movement of the grenade for breaking the grenade upon impact therewith. 120

7. Grenade supporting structure comprising 125 a bracket, a plurality of arms pivotally associated with said bracket, each arm having means for supporting and holding a grenade, resilient means associated with each arm for swinging said arm, said grenades being movable by said resilient means in intersecting paths, and heat controlled means for holding said arms against swinging. 130

8. Grenade supporting structure comprising a bracket, a plurality of arms pivotally associated with said bracket, each arm having means for supporting and holding a grenade, resilient means associated with each arm for swinging said arm, said grenades being movable by said resilient means in intersecting paths, and single heat controlled means for holding said arms against swinging.

9. Grenade supporting structure comprising a bracket, a plurality of arms pivotally associated with said bracket, each arm having means for supporting and holding a grenade, resilient means associated with each arm for swinging said arm, heat controlled means for holding said arms against swinging, and means engageable by said grenades when released from said heat controlled means for breaking said grenades.

10. Grenade supporting structure comprising a bracket, a plurality of arms pivotally associated with said bracket, each arm having means for supporting and holding a grenade, resilient means associated with said arms for swinging the arms in opposite directions, heat controlled means for holding said arms against swinging, and means engageable by the grenades when released from said heat controlled means for breaking said grenades.

In witness whereof, I have hereunto set my hand this 3rd day of March, 1928.

WILHELM B. BRONANDER.
